COMBINED ROSARY AND CONTAINER THEREFOR

Thomas R. Duggan, 137 E. 32nd St.,
Brooklyn, N.Y. 11226

Filed Aug. 14, 1967, Ser. No. 8,246

Term of patent 14 years

(Cl. D45—1)

FIG. 1

FIG. 2

FIG. 3

FIG. 4

FIG. 1 is a front edge and top perspective view of a combined rosary and container therefor showing my new design;

FIG. 2 is a side elevation thereof;

FIG. 3 is a rear elevation thereof; and

FIG. 4 is a bottom plan view of the rosary.

I claim:

The ornamental design for a combined rosary and container therefor, substantially as shown.
